(57) CLAIM

The design for a wine refrigerator, as shown and described.

DESCRIPTION

FIG. 1 is a front perspective view of a wine refrigerator showing my new design.

FIG. 2 is a front elevational view thereof; and,

FIG. 3 is a left side elevational view thereof.

The broken lines shown in FIGS. 1 to 3 are for the purpose of illustrating environment and form no part of the claimed design.

1 Claim, 3 Drawing Sheets

FIG. 3
